CONNECTION DEVICE TO MAINTAIN STACKED
TAB MEMBERS IN ELECTRICAL ENGAGEMENT

John Hammond Geis, Jr., Harrisburg, Pa., assignor to
AMP Incorporated, Harrisburg, Pa.

Filed Jan. 6, 1966, Ser. No. 493

Term of patent 14 years

(Cl. D26—1)

FIGURE 1 is a perspective view of a connection device to maintain stacked tab members in electrical engagement;

FIGURE 2 is a side elevational view thereof;

FIGURE 3 is a front elevational view thereof;

FIGURE 4 is a rear elevational view thereof;

FIGURE 5 is a top plan view thereof; and

FIGURE 6 is a bottom plan view thereof.

I claim:

The ornamental design for a connection device to

maintain stacked tab members in electrical engagement, as shown and described.
